ATTORNEY

UNITED STATES PATENT OFFICE

FRANK KERTÉSZ, OF POTTSTOWN, PENNSYLVANIA

AEROPLANE

Application filed December 6, 1929. Serial No. 412,204.

This invention relates to aeroplanes, the general object of the invention being to provide means whereby the plane has great safety in flight, can be moved vertically in rising and landing and can be caused to travel either forwardly or rearwardly and can be flown at a very low speed or a high speed.

Another object of the invention is to provide the plane with pairs of forward and rearward vertically arranged rudders and forward and rearward pairs of horizontally arranged rudders, each pair of rudders being driven by a power plant, with means for controlling the pitch of the blades of the propellers to enable the plane to move vertically and horizontally.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of the improved craft, with parts broken away.

Figure 2 is a top plan view thereof.

Figure 3 is a front view.

Figure 4 is a section on line 4—4 of Figure 2.

Figure 5 is a section on line 5—5 of Figure 4.

Figure 6 is a section on line 6—6 of Figure 4.

Figure 7 is a fragmentary plan view of one of the vertical propellers and its associated parts.

Figure 8 is a section on line 8—8 of Figure 7.

Figure 9 is a section on line 9—9 of Figure 8.

Figure 10 is an end view of one of the clutch members.

Figure 11 is a partial view of one of the propellers, showing the ribbed face of the holders for the blades thereof.

Figure 12 is an edge view of Figure 11.

Figure 13 is a section on line 13—13 of Figure 12.

Figure 14 is a view of the ribbed face of the member to which the holders of the blades are pivoted.

Figure 15 is a section on line 15—15 of Figure 7.

Figure 16 is a detail sectional view showing one of the covering means used to cover the exposed parts.

Figure 17 is a detail sectional view showing how a power plant is supported.

Figure 18 is a view of one of the levers.

In these drawings, the letter A indicates the fuselage of the craft, which is provided with the landing wheels 1, the windows 2 and the doors 3. The tail part of the fuselage carries the usual vertical and horizontal rudders 4 and a wing 5 is suitably attached to the fuselage in spaced relation from the top thereof, as shown in Figures 1 and 3. Four transverse supports 6 are suitably attached to the top of the fuselage and project beyond the sides of the same, two of these supports 7 being arranged under the side edges of the wings, with another support arranged adjacent the front end of the fuselage and the fourth support arranged adjacent the rear end thereof.

A power plant and its housings are supported by the right hand ends of the middle supports, as shown generally at 7, and a similar power plant assembly is supported by the left hand ends of the middle supports, as shown at 8. Each power plant assembly includes a shaft 9 driven from the power plant and having a hub 10 at each end thereof which is formed with a head 11 at its outer end, the outer face of each head having a plu-

rality of ridged ribs 12 thereon, the grooves formed by the ribs receiving the ridged ribs 13 formed on the pair of holders 14 to each of which a propeller blade 15 is attached by 5 the bolts 16. The ribs of the two holders 14 are pivotally connected with the ribs of the head by a pin 17 passing through the centers of the ribs so that the two holders are supported for rocking movement on the head 10 and thus the pitch of the propeller blades can be varied. A link 18 is pivoted to each holder and these links extend through the notches 19 arranged at opposite sides of the head 11 and are pivoted to opposite sides of 15 the flange of a sliding cap 20 on the hub 10 of the shaft 9.

A rod 21 is slidably arranged in each bearing part 22 of the power plant assemblies and the hub 23 of a fork 24 is fastened to the outer 20 end of the rod, the fork engaging a groove 25 in the member 20, so that when the rod 21 is moved inwardly, the fork will move the member 20 in the same direction and thus the links 18 will be caused to tilt the propeller 25 blade holders on their pivots 17 to change the pitch of the blades.

A shaft 26 is journaled on each middle support 6 and has an arm 27 at each end thereof which is connected by a link 28 with a 20 projection 29 on the hub 23, so that when the shaft 26 is rocked, the member 20 and its associated parts will be slid in one direction or the other to change the tilt of the blades. The rear shaft 26 is connected by a 25 link 30 with a hand lever 31 arranged in the fuselage, so that by manipulating this hand lever, the blades of the rear vertical propellers can have their pitch changed. The front shaft 26 is attached by the connections 32 to 40 a lever 33, so that by manipulating this lever, the pitch of the blades of the forward vertical propellers can be varied. As will be seen, the same power plant operates a forward propeller and a rearward propeller.

45 A power plant assembly, shown generally at 34, is supported by the end supporting members 6 and the shafts 35 of these assemblies are connected by the beveled gears 36 with the vertical shafts 37 which drive the 50 horizontal propellers 38, one of which is arranged at each end of each forward and rearward supporting member 6. The blades of each propeller are connected in the same manner with the heads of the shafts, as before described, so that the blades can have their 55 pitch changed and the forks 39 for shifting the members 20 of each pair of propellers 38 are connected by the links 40 with the arms 41 on a shaft 42, the shaft 42 for the front set 60 of propellers being attached by the connections 43 with a hand lever 44, while the shaft 42 for the rear set of propellers is attached by the connections 45 with a hand lever 46 so that by manipulating these hand levers 44 and 65 46, the pitch of the blades of the propellers

38 can be changed, as before described. I prefer to place the levers 44 and 46 close together, so that they can be manipulated by one hand, when desired.

The gears 36 are enclosed by the housings 70 47 and all exposed parts are covered by canvas or the like, as shown at 48 in Figure 16. The supports for the motor assemblies are connected together at their inner ends by the trough-shaped parts 49, as shown in Figure 75 17, so that portions of the motors extend into the trough-shaped member.

From the foregoing it will be seen that I have provided two pairs of vertical propellers and two pairs of horizontal propellers, the propellers being arranged at the sides of the fuselage, with the wing 5 arranged on a plane which is substantially the same as the plane of the top of the circular path of the vertical propellers, as shown in Figure 1. 85 Each pair of propellers is driven from one power plant and the pitch of the forward pair of vertical propellers is controlled from a single lever, the pitch of the rear pair of vertical propellers being controlled from another lever and the pitch of the first pair of horizontal propellers being controlled by a third lever and a fourth lever controlling the pitch of the blades of the rear pair of horizontal propellers. 90

When the pilot wishes to take off, all the propeller blades should be placed in neutral position. Then the four motors are started. After the propellers reach a high speed, the lever 31 is moved back with the right hand and the lever 33 moved forwardly with the left hand. These actions will place the blades of the forward vertical propellers 15 in a position where they will tend to move the craft forwardly and the two rear propellers 15 will be tending to move the craft rearwardly. Thus the craft is prevented from moving either forwardly or rearwardly and the air from the four propellers is compressed and forced up under the wing, which tends to lift the craft. Then the two levers 44 and 46 are pulled backwardly at the same time, which will move the horizontal propellers 38 into operative position, and these propellers will move the craft upwardly. If the craft does not move upwardly on an even keel, the blades of the propellers 38 can be adjusted by the hand levers so that the uneven pull can be adjusted, so that the craft will assume an even keel as it moves upwardly. 110

When the craft reaches the desired height, the control stick is grasped by the left hand and the lever 31 by the right hand and then said lever 31 is moved forwardly a certain distance to reverse the blades of the rear propellers 15 so that these propellers will act with the front propellers 15 to drive the craft forwardly. The machine will now be traveling forwardly and still rising. Then the left hand of the pilot takes hold of the 125 130

levers 44 and 46 and pushes such levers forwardly until all four lifting propellers 38 are in neutral position. The craft now is traveling forwardly and all the pilot has to do is to tend to his regular controls. It is preferable to have all four lifting propellers rotate at high speeds at all times in neutral position because in this position, they give the machine a greater lifting capacity and balance it better without hindering its flight. When the plane is flying at high speed, the two motors operating the lifting propellers can be reduced in speed to save fuel, but they should never be stopped entirely. When it is desired to land the craft, the propellers 15 are set as in rising so that they will work against each other and drive the air under the wing and the lifting propellers are set at such a pitch as to permit the craft to move downwardly slowly and thus land without damage. When in flight and it is desired to fly at low speed, the rear propellers 15 can be set so that they will pull backwardly slightly and thus act as a check on the front propellers. If desired, the propellers 15 can be set so as to cause the craft to move rearwardly.

With this invention, a plane can land on small landing fields, on roofs, ships and the like, and can take off from such places. One can learn to fly easier with this improved aeroplane than with the old type because the learner has more time to think and it is not necessary to travel at high speed.

35 Each of the levers 31, 33, 44 and 46 is preferably arranged as shown in Figure 18.

Gas and oil tanks 50 are located at the bottom of the fuselage. A vacuum tank 52 is located at the center of the wing, as shown 40 in Figure 1, and acts to distribute the gas from the gas tank to the motors.

It is thought from the foregoing description that the advantages and novel features of the invention will be readily apparent.

45 It is to be understood that changes may be made in the construction and in the combination and arrangement of the several parts, provided that such changes fall within the scope of the appended claims.

50 What I claim is:—

1. An aeroplane comprising a fuselage, a wing connected with the fuselage above the same and spaced therefrom, supporting means extending laterally from the sides of the 55 fuselage at the top thereof, a pair of lifting propellers at each end of the front supporting means, a pair of lifting propellers at each end of the rear supporting means, front and rear vertically arranged propellers supported from the ends of the middle supporting means, power means for driving each pair of propellers and means for changing the pitch of the propeller blades whereby the plane can be caused to move vertically and horizontally.

2. An aeroplane comprising a fuselage, a wing connected with and supported above the fuselage, four transverse supports connected with the top of the fuselage, a lifting propeller at each end of each of the front and rear supporting means, a longitudinally extending shaft supported at each end of the middle supporting means, a propeller at each end of each shaft, said propellers being vertically arranged, a power plant for driving each shaft, a power plant for driving each pair of lifting propellers, manually operated means for adjusting the pitch of the blades of each pair of lifting propellers, manually operated means for adjusting the pitch of the forward driving propellers and manually operated means for adjusting the pitch of the rearward driving propellers.

3. An aeroplane comprising a fuselage, a wing connected with and supported above the fuselage, four transverse supports connected with the top of the fuselage, a lifting propeller at each end of each of the front and rear supporting means, a longitudinally extending shaft supported at each end of the middle supporting means, a propeller at each end of each shaft, said propellers being vertically arranged, a power plant for driving each shaft, a power plant for driving each pair of lifting propellers, manually operated means for adjusting the pitch of the blades of each pair of lifting propellers, manually operated means for adjusting the pitch of the forward driving propellers, manually operated means for adjusting the pitch of the rearward driving propellers, each of such means including a hand lever arranged in the fuselage, with the hand levers which control the pitch of the blades of the lifting propellers arranged close together so that they can be manipulated by one hand, when desired.

4. An aeroplane comprising a number of lifting propellers, a pair of forward driving propellers, a pair of rearwardly driving propellers, power means for driving the propellers and means for adjusting the pitch of the blades of each propeller, such means comprising a ribbed head on the end of each propeller shaft, said ribs being ridged, a pair of blade holders for the blades of each propeller, ridged ribs on each holder, the ribs on the holders fitting between the ribs on the head, a central pivot pin passing through the ribs for pivotally connecting the holders with the head, a sliding member on the shaft, links connecting opposite sides of the sliding member with opposite sides of the holders, whereby sliding movement of the member will cause the holders to pivot on the head and manually operated means for moving the sliding members.

5. An aeroplane comprising a fuselage, a wing supported from and above the fuselage, a pair of transverse supporting members con-

5 nected with the top of the fuselage and ar-
ranged under the front and side edges of
the wing, a power plant assembly longi-
tudinally arranged and supported at each end
of said pair of supporting members, said
assembly including a shaft, a propeller on
each end of each shaft, whereby the two pro-
pellers on each shaft are driven from the
power plant, a transversely arranged sup-
porting member adjacent the front of the
fuselage, a similar member arranged adjac-
ent the rear of the fuselage, a power plant
assembly carried by each supporting mem-
ber, each assembly including a shaft, a ver-
tical shaft at each end of each front and rear
supporting member, gears connecting the
vertical shafts with the power plant shafts,
a horizontal propeller driven from each ver-
tical shaft, manually operated means for ad-
justing the blades of each pair of horizontal
propellers, manually operated means for ad-
justing the blades of the forward driving
propellers and manually operated means for
adjusting the blades of the rearward driving
propellers.

6. An aeroplane comprising a fuselage, a
wing supported from and above the fuselage,
a pair of transverse supporting members con-
nected with the top of the fuselage and ar-
ranged under the front and side edges of the
wing, a power plant assembly longitudinally
arranged and supported at each end of said
pair of supporting members, said assembly
including a shaft, a propeller on each end of
each shaft, whereby the two propellers on
each shaft are driven from the power plant,
a transversely arranged supporting member
adjacent the front of the fuselage, a similar
member arranged adjacent the rear of the
fuselage, a power plant assembly carried by
each supporting member, each assembly in-
cluding a shaft, a vertical shaft at each end
of each front and rear supporting member,
gears connecting the vertical shafts with the
power plant shafts, a horizontal propeller
driven from each vertical shaft, manually
operated means for adjusting the blades of
each pair of horizontal propellers, manually
operated means for adjusting the blades of
the forward driving propellers, manually
operated means for adjusting the blades of
the rearward driving propellers, horizontal
and vertical rudders at the rear end of the
fuselage and means for controlling the same
from the interior of the fuselage.

7. An aeroplane comprising a fuselage, a
wing supported from and above the fuselage,
a pair of transverse supporting members con-
nected with the top of the fuselage and ar-
ranged under the front and side edges of the
wing, a power plant assembly longitudinally
arranged and supported at each end of said
pair of supporting members, said assembly
including a shaft, a propeller at each end
of each shaft, whereby the two propellers

on each shaft are driven from the power
plant, a transversely arranged supporting
member adjacent the front of the fuselage, a
similar member arranged adjacent the rear
of the fuselage, a power plant assembly car-
ried by each supporting member, each as-
sembly including a shaft, a vertical shaft at
each end of each front and rear supporting
member, gears connecting the vertical shafts
with the power plant shafts, a horizontal
propeller driven from each vertical shaft,
manually operated means for adjusting the
blades of each pair of horizontal propellers,
manually operated means for adjusting the
blades of the forward driving propellers,
manually operated means for adjusting the
blades of the rearward driving propellers,
horizontal and vertical rudders at the rear
end of the fuselage, means for controlling
the same from the interior of the fuselage,
tanks in the bottom of the fuselage for oil
and gas, a vacuum tank connected with the
under part of the wing for distributing gas
from the gas tank to the motors and cov-
ering means for those parts of the device
which are exposed.

In testimony whereof I affix my signature.

FRANK KERTÉSZ.
